UNITED STATES PATENT OFFICE.

WILLIAM H. GRINDLEY, OF CONGLETON, ENGLAND.

DESIGN FOR A EWER.

SPECIFICATION forming part of Design No. 29,569, dated November 1, 1898.

Application filed September 9, 1898. Serial No. 690,603. Term of patent 3½ years.

To all whom it may concern:

Be it known that I, WILLIAM H. GRINDLEY, a subject of the Queen of Great Britain, residing at Congleton, Chester county, England, have invented and produced a certain new and original Design for a Ewer; and I do hereby declare the following to be a full, clear, and exact description of the same, reference being had to the accompanying drawings, forming part hereof.

In the drawings, Figure 1 is a side view of a ewer embodying my design, and Fig. 2 is a top view and partial section of the same upon the plane of the line 2 2 in Fig. 1.

15 The leading features of my design are as follows: The body of the ewer *a* consists of a substantially smooth surface, wide at the top and tapering in an easy elliptical curve toward the bottom, where it is expanded into 20 a foot *f*. At the top the body *a* terminates in a circular flange *b*, above which is placed a short neck *c*, concavely curved inward toward the upper rim *r* of the ewer and provided with a downwardly-curved lip *l*. A 25 handle *h*, secured to the neck at its rearmost point, is curved upward and then downward and inward toward the body *a*, which it meets at *d*. Another section of the handle, *i*, is reversed and curved outward to meet the main 30 handle at *e*.

Upon the body, foot, neck, and handle of the ewer are placed certain ornamental deco-

rations, as follows: The body is decorated with six floral garlands, of which three can be seen from each side. These garlands are 35 all alike and consist of a central flower *g* at the lowermost point of the garland and similar flowers *j* at the uppermost points thereof, the width of each garland diminishing toward the top. The flowers of which the garlands are 40 composed are conventionalized, but resemble edelweiss.

At the bottom of the body of the ewer is placed a series of upwardly-projecting flower-like scrolls *k*, between each pair of which are 45 somewhat shorter scrolls *m*. The foot *f* is decorated with similar scroll-like forms *n*.

The neck *c* of the ewer is decorated with twig-like embossings *p*, each terminating in flower-shaped forms *q*.

The handle is embossed with the edelweiss-shaped flower at *s* and with similar forms at *t* and *v*.

What I claim is—

The design for a ewer substantially as shown 55 and described.

In witness whereof I have hereunto set my hand, this 26th day of August, 1898, in the presence of two subscribing witnesses.

WILLIAM H. GRINDLEY.

Witnesses:

Wm. HARRISON BRADLEY,
JOHN H. COPESTAKE.
